UNITED STATES PATENT OFFICE

DAVID L. GALLUP, OF SOUTH BEND, INDIANA, ASSIGNOR TO BENDIX BRAKE COMPANY,
OF SOUTH BEND, INDIANA, A CORPORATION OF ILLINOIS

BRAKE SHOE

Application filed November 30, 1928. Serial No. 322,677.

This invention relates to articles such as 5
brake shoes, and is illustrated as embodied
in one of two interchangeable shoes of an in-
ternal expanding brake. An object of the
invention is to provide an inexpensive but
extremely strong brake shoe so designed as
to be symmetrical with respect to a line di-
viding the shoe in equal parts.

In the illustrated embodiment a brake shoe
10 is disclosed wherein an outer band forming
the friction face of the shoe is permanently
secured to a separate stiffening web by fas-
tenings symmetrically arranged on either
15 side of a center line dividing the shoe. These
fastenings may comprise spot welds aug-
mented by tongue-and-slot means, the
tongues preferably provided on the web pe-
riphery and nesting within slots in the rim.

There is thus provided a brake shoe capable
20 of being reversed end for end within the
brake.

The above and other objects and features
of the invention, including various novel and
desirable details of construction will be ap-
25 parent from the following description of the
illustrative embodiment shown in the accom-
panying drawing, in which:

Figures 1 and 2 are side elevation and bot-
tom plan views, respectively, of my novel
30 brake shoe;

Figure 3 is a section through the shoe, on
the line 3—3 of Figure 1 passing through one
of the welds; and

Figure 4 is an enlarged fragmentary view,
35 in longitudinal section of one end of the shoe
showing the tongue-and-slot connection.

In that embodiment of my invention il-
lustrated I preferably fabricate the shoe in
two principal parts, viz: (1) an outer arcuate
40 band or rim 22, to which the brake lining 24
is secured by spaced rivets 26, and (2) a sepa-
rate stiffening web 28 having its outer edge
curved on the same radius as the inner face
45 of the band 22 and resting against that face.
I further prefer to provide the rim with
spaced embossments 30 (Figure 3) at which
points the rim may be spot welded to the web.
As a means for resisting the shearing action
50 of the brake drum tending to separate the
band from the web lengthwise of the shoe, I

prefer to provide tongue-and-slot means addition-
ally connecting the band and web and re-
lieving the spot welds of shearing strain.
To this end the web is provided with three
tongues 32 and I prefer that they be located 55
one at each end of the shoe and one in the cen-
ter thereof. These tongues nest within cor-
respondingly shaped slots in the rim of the
shoe. Washers 34 may be suitably secured
to the ends of the shoes as disclosed in Figure 60
4, a pair at each end, to provide bearings for
the associated brake parts.

As a further and important feature of my
invention, I suggest that the halves of the
shoes be mirror images of each other, that 65
is to say that the several fastenings includ-
ing both the tongues and the welds be sym-
metrically arranged with respect to a line
X—X, Figure 2. The rim and web geometry
is likewise the same on both sides of this cen- 70
tral line.

A strong and inexpensive but withal ef-
fective shoe is thus provided admirably
adapted for a two-shoe brake wherein the
shoes are interchangeable. Furthermore by 75
virtue of the symmetrical construction de-
scribed, the manufacture of the several parts
of the shoe is facilitated in that the punch-
ing, pressing and other operations may be
simplified.

While one illustrative embodiment has
been described in detail, it is not my inten-
tion to limit the scope of the invention to that
particular embodiment, or otherwise than by
the terms of the appended claims.

I claim:

1. A brake shoe comprising at least two
principal parts, viz: (1) an outer arcuate
band formed with a comparatively small
number of embossments lying in or imme- 90
diately adjacent a longitudinally extending
line dividing the band in equal parts and fur-
ther provided with a plurality of spaced slots
also lying in or immediately adjacent said
line, and (2) a separate stiffening web hav- 95
ing tongues at its outer edge projecting into
the aforementioned slots and having its outer
edge engaging the inner face of said band be-
tween the openings, said band being secured
to the web at least in part by spot welds at 100

the aforementioned embossments, the welds and tongues being symmetrically spaced from the center of the shoe to provide a shoe, one half of which is the mirror image of the remaining half.

2. A brake shoe comprising a rim having longitudinally disposed slots, a reinforcing web for the rim, tongues on the web engaging the slots and bosses on the rim engaging the respective sides of the web.

3. A brake shoe comprising a rim having longitudinally disposed slots, a web for the rim having tongues engaging the slots and spaced bosses on the rim arranged in pairs, one on each side of the web and spot-welded thereto.

In testimony whereof, I have hereunto signed my name.

DAVID L. GALLUP.
